(57) **CLAIM**

The ornamental design for a levitating lamp, as shown and described.

DESCRIPTION

FIG. 1 is a perspective view of a levitating lamp showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof, showing the levitating lamp in an alternate state of use.

The broken lines in the drawings depict portions of the levitating lamp that form no part of the claimed design.
